MACHINES FOR LASTING SHOES

Edward Quinn, Peabody, and Edward F. Mitchell, Beverly, Mass., assignors to United Shoe Machinery Corporation, Boston, Mass., a corporation of New Jersey

Filed Mar. 27, 1962, Ser. No. 182,811

42 Claims. (Cl. 12—11.2)

This invention relates to a machine for lasting shoes, and particularly to a novel and improved machine for simultaneously lasting the upper materials of a shoe and securing the lasting margin of such materials in lasted position to a so-called flat rib on an insole, together with a welt, in accordance with the method disclosed and claimed in United States Letters Patent No. 2,832,975, issued May 6, 1958 on an application filed in the names of Ralph E. Pearsall and Lawrence A. Severy. As is suggested in that patent, the novel method claimed therein may be carried out by a simple machine including power-operated upper tensioning grippers, staple forming and driving mechanism including a nozzle, a driver and an anvil, and means for guiding and feeding a welt to a position to be secured to the insole rib, together with a lasting margin of the tensioned upper materials, by the staples as they are driven. It is a principal object of this invention to provide a novel and improved machine of this general type which embodies several novel features and combinations of features for facilitating the practicing of the aforementioned method. It will be understood, however, that in their broader aspects features of the invention are not necessarily limited to use in a machine for practicing the prior patented method or to the exact mechanical construction shown.

With the foregoing general object in view and in accordance with a feature of the invention, the herein illustrated machine, which has a power operated gripper for tensioning the upper materials of a shoe over a last in different locations, successively, along the marginal edge of the bottom of the shoe from the breast line to the tip line on one side of the shoe and from the tip line to the breast line on the opposite side of the shoe, and staple forming and driving means operating in time relation to said gripper for securing the lasting margin of the tensioned upper materials, and also a welt, to the so-called flat rib on the insole of the shoe at each of said locations, is also provided with means associated with the staple forming and driving means for varying the length of the staple, together with means for rendering the upper tensioning gripper operative or inoperative, and a foot treadle movable by the operator to cause short staples to be formed and inserted when the gripper is operating and long staples to be formed and driven when the gripper is rendered inoperative. Thus, when the machine is operating along the opposite sides of a shoe, where the upper has not been previously tensioned, the gripper may be rendered operative to tension the upper and the staple forming and driving mechanism set to drive short staples, while, when the lasting operation reaches the toe end of the shoe, where the upper materials will have been previously tensioned and shaped to the toe end of the last, the gripper may be rendered inoperative and at the same time, the staple forming and driving mechanism set to drive a long staple needed because of the extra thickness of the upper materials, i.e., upper, box toe, and lining, in this location.

In common with staple lasting machines of the progressive type, the staple clenching anvil of the staple forming and driving mechanism of the herein illustrated machine is adapted to engage the insole rib in a location offset somewhat in the direction of feed of the shoe from the upper tensioning gripper for guiding the shoe

2

and also for supporting the shoe against lateral movement in response to the pull of the gripper. Because of the mentioned offset location of the anvil, the pull of the gripper also has a tendency to swing the shoe about the anvil as a fulcrum and to overcome this tendency, in accordance with another feature of the invention, there is provided in the herein illustrated machine an auxiliary support which is movable from a retracted and inoperative position remote from the insole rib to an operative position for engaging the rib, together with means operating in time relation to the gripper for so moving the auxiliary support between these two positions that the auxiliary support is retracted while the shoe is being fed along, between operations of the gripper and the staple forming and driving means, thereby facilitating such feeding of the shoe by the machine and the guiding of the shoe by the operator, and is moved to its operative position in engagement with the insole rib, during the operation of the gripper, thereby to provide additional support for the shoe against lateral and swinging movement in response to the pull applied on the upper materials by the gripper.

In order to provide effective feeding of the shoe, thereby to assure a uniform spacing between the different locations at which the upper materials are tensioned and/or fastened to the insole rib, by fastening driven through the welt, upper materials and insole rib, the herein illustrated machine has mechanical feeding means which, in accordance with another feature of the invention, is operated by, and in time relation to the fastening inserting means. More particularly, this feeding means comprises a gripper having a smooth jaw for engaging the grain side of the welt with very little friction and another jaw provided with an annular rib for engaging the flesh side of the welt with great frictional resistance to relative linear movement between the jaw and the welt but with very little frictional resistance to relative rotary movement between said jaw and the welt. Thus, when this shoe feeding gripper is closed on the welt and moved in a direction to feed the shoe, a positive linear feeding action is obtained. Yet, at the same time, very little, if any, resistance to relative rotary movement, such as may be required in guiding the shoe, is set up by the feeding gripper.

In lasting the upper materials of a shoe and securing the lasting margin of the tensioned upper materials together with a welt to the so-called flat rib of an insole of the type disclosed in Patent 2,832,975, mentioned above, when the fastening inserting means is operated to insert a fastening, the welt should be disposed flatly on the shoe bottom over the lasting margin of the upper materials and insole rib in the location where the fastening is to be driven and closely adjacent to the upper tensioning gripper. For holding the welt in this position, a guide is provided in the herein illustrated machine which, in accordance with still another feature of the invention, is adapted to surround the welt in a location between the gripper and the fastening inserting mechanism, i.e., the staple forming and driving means, and is pivotally mounted for movement into one position for holding the welt over the bottom of the shoe in generally parallel relation thereto and to another position for swinging the welt upwardly out of the way of the gripper, together with means operated by a member associated with the staple forming and driving means and in time relation to the gripper and said staple forming and driving means for moving the guide means to its second position when the gripper is operated and for returning the guide means to its first position prior to the operation of the staple forming and driving means.

The above and other objects and features of the invention, including, among other things, novel means for de-

flecting the marginal portion of the upper materials toward the bottom of the shoe during the operation of the gripper, thereby to distribute the loose upper materials more uniformly along the marginal edge of the shoe bottom, will appear in the following detailed description of the preferred embodiment of the invention which is illustrated in the accompanying drawings and will be pointed out in the claims.

In the drawings,

FIG. 1 is a view in side elevation of a machine embodying the features of this invention; 10

FIG. 2 is a view in front elevation of a part of the machine shown in FIG. 1;

FIG. 3 is a view in front elevation and at an enlarged scale of the operating head of the machine shown in FIG. 1; 15

FIG. 4 is a view in side elevation of the head of the machine with certain parts removed therefrom and others broken away to simplify the disclosure;

FIGS. 5 and 6 are views in side elevation and at an enlarged scale of a clutch control mechanism associated with the machine shown in FIG. 1, these views showing the parts in two different positions;

FIG. 7 is a plan view of the clutch control mechanism shown in FIGS. 5 and 6 as viewed from a plane indicated by the line VII—VII in FIG. 6 and looking in the direction of the arrows; 20

FIG. 8 is a view in rear elevation of the clutch control mechanism shown in FIG. 6;

FIG. 9 is a plan view of certain of the operating elements of the clutch control mechanism shown in FIG. 5 with one element broken away and another shown in horizontal section substantially on line IX—IX of FIG. 5 and looking in the direction of the arrows;

FIG. 10 is a view in vertical section through the head of the machine;

FIG. 11 is a view in side elevation of the head of the machine, similar to that of FIG. 4 but with additional parts removed to show the interior of the head of the machine;

FIG. 12 is a view in front elevation and at an enlarged scale of staple forming and driving mechanism associated with the head of the machine;

FIG. 13 is a view in front elevation of a portion of the mechanism shown in FIG. 12;

FIG. 14 is a view in horizontal section substantially on line XIV—XIV of FIG. 13 and looking in the direction of the arrows;

FIG. 15 is a view in horizontal section substantially on line XV—XV of FIG. 16;

FIG. 16 is a view in side elevation of the staple forming and driving mechanism shown in FIG. 12 with certain parts in vertical section substantially on line XVI—XVI of FIG. 13 and looking in the direction of the arrows;

FIG. 17 is a view in vertical section on line XVII—XVII of FIG. 12 and looking in the direction of the arrows;

FIG. 18 is a schematic perspective view of certain parts of the staple forming and driving mechanism shown in FIG. 12;

FIG. 19 is a view in side elevation of certain operating elements associated with the staple forming and driving mechanism as seen from the left-hand side of the machine and with various other parts of the machine removed to simplify the disclosure;

FIG. 20 is a view similar to that of FIG. 19 but with the operating elements shown in different positions assumed during the operation of the machine;

FIG. 21 is a view in front elevation of the left-hand portion of the head of the machine with some parts omitted to simplify the disclosure and showing especially elements associated with the staple forming and driving mechanism;

FIG. 22 is a view in side elevation of the head of the

machine as seen from the left-hand side thereof, showing especially operating elements associated with the staple forming and driving mechanism and with various other operating elements removed or omitted to simplify the disclosure;

FIG. 23 is a view in side elevation of a cam and a cam operating lever associated with the staple forming and driving mechanism;

FIG. 24 is a view in front elevation of a portion of the mechanism which is shown in FIG. 21;

FIG. 25 is a plan view of operating elements shown in FIG. 26;

FIG. 26 is a view in side elevation of a portion of the mechanism shown in FIG. 24, this view being a vertical section substantially on line XXVI—XXVI of FIG. 24 and looking in direction of arrows;

FIG. 27 is a view in horizontal section substantially on line XXVII—XXVII of FIG. 24 and looking in the direction of the arrows;

FIG. 28 is a view in side elevation of certain parts shown in FIG. 21 as seen from the left-hand side of the machine;

FIG. 29 is a view in front elevation of a portion of one of the operating elements also appearing in FIG. 21;

FIG. 30 is a plan view of certain operating elements of the mechanism shown in FIG. 21;

FIG. 31 is a plan view similar to that of FIG. 30 but showing the operating elements in different positions;

FIG. 32 is a view in side elevation and at an enlarged scale of portions of certain operating elements shown in FIG. 21 as seen from the left-hand side of that figure;

FIG. 33 is a view similar to that of FIG. 32 but with the operating elements in different positions;

FIG. 34 is a view in side elevation of a portion of the head of the machine as seen from the right-hand side thereof and with certain operating elements of the machine omitted to simplify the disclosure;

FIG. 35 is a view in front elevation of operating elements shown in FIG. 34;

FIG. 36 is a view in horizontal section substantially on line XXXVI—XXXVI of FIG. 35 looking in the direction of the arrows;

FIG. 37 is a view in horizontal section substantially on line XXXVII—XXXVII of FIG. 35 and looking in the direction of the arrows;

FIG. 38 is a view in front elevation of a portion of the mechanism shown in FIG. 35;

FIG. 39 is a view in side elevation of a shoe rest forming part of the machine;

FIG. 40 is a plan view of the shoe rest as seen from below;

FIG. 41 is a plan view of a portion of one of the operating elements of the machine;

FIGS. 42 and 43 are plan and end elevation views, respectively, of the operating element shown in FIG. 41;

FIGS. 44 and 45 are plan and side elevation views, respectively, of portions of other operating elements associated with the machine;

FIG. 46 is a view in end elevation of one of the operating elements shown in FIG. 45 as seen from the right-hand end of that figure;

FIG. 47 is a view in side elevation of this operating element as viewed from the side opposite to that appearing in FIG. 45;

FIG. 48 is a view in side elevation of portions of the same operating elements shown in FIGS. 45 and 46 and also showing a portion of another operating element associated therewith;

FIGS. 49, 50 and 51 are views in section taken substantially on line L—L in FIG. 48 and looking in the direction of the arrows, these views showing the parts in different positions assumed during the operation of the machine;

FIG. 52 is a view in front elevation of a latch mechanism associated with the operating elements shown in

FIG. 48 as seen from the plane indicated by the lines LII—LII in FIG. 48 and looking in the direction of the arrows;

FIG. 53 is a plan view of the latch mechanism shown in FIG. 52 with the latch shown in section substantially on line LIII—LIII of FIG. 52 and looking in the direction of the arrows;

FIG. 54 is a plan view of a feeding mechanism associated with the machine;

FIG. 55 is a view in section substantially on line LV—LV of FIG. 58 and looking in the direction of the arrows;

FIG. 56 is a view in side elevation of the feeding mechanism shown in FIG. 54, this mechanism being shown as viewed from the right-hand side of the machine;

FIG. 57 is a view in section substantially on line LVII—LVII of FIG. 56 and looking in the direction of the arrows, this view showing only a part of the mechanism appearing in FIG. 56;

FIG. 58 is a plan view of one of the operating elements associated with the feeding mechanism;

FIG. 59 is a view in front elevation of the feeding mechanism;

FIG. 60 is a view in front elevation of one of the operating elements of the feeding mechanism;

FIG. 61 is a detail view at an enlarged scale of a portion of the element shown in FIG. 60;

FIG. 62 is a view in side elevation of the feeding mechanism as seen from the left-hand side of the machine, this view also showing the shoe rest and a welt guide member associated therewith;

FIG. 63 is a diagrammatic plan view illustrating the action of the feeding mechanism;

FIG. 64 is a diagrammatic plan view similar to that of FIG. 63 but also showing the shoe rest and the welt guide member;

FIG. 65 is a plan view of a portion of a welt tilting mechanism associated with the machine;

FIG. 66 is a view in side elevation of the welt tilting mechanism shown in FIG. 65;

FIG. 67 is a view in section substantially on line LXVII—LXVII of FIG. 66 and looking in the direction of the arrows;

FIG. 68 is a view in section substantially on line LXVIII—LXVIII of FIG. 67 and looking in the direction of the arrows;

FIG. 69 is a view in front elevation of that portion of the welt tilting mechanism which is shown in FIG. 66;

FIG. 70 is a view in front elevation of the entire welt tilting mechanism;

FIG. 71 is a view in side elevation of the welt tilting mechanism shown in FIG. 70 as viewed from the left-hand side of the machine;

FIG. 72 is a view in section substantially on line LXXII—LXXII of FIG. 71 looking in the direction of the arrows;

FIG. 73 is a plan view of a portion of the welt tilting mechanism;

FIG. 74 is a view in end elevation of a part associated with the welt tilting mechanism as indicated by the line LXXIV—LXXIV in FIG. 73 and looking in the direction of the arrows;

FIGS. 75, 76 and 77 are front and end elevation views, respectively, of another part associated with the welt tilting mechanism;

FIG. 78 is a view in section substantially on line LXXVIII—LXXVIII in FIG. 71 and looking in the direction of the arrows;

FIG. 79 is a plan view of certain parts associated with the welt tilting mechanism;

FIG. 80 is a perspective view of a member associated with the welt tilting mechanism;

FIG. 81 is a view in section substantially on line

LXXXI—LXXXI of FIG. 79 and looking in the direction of the arrows and with another operating element shown;

FIG. 82 is a view in section substantially on line LXXXII—LXXXII in FIG. 79 and looking in the direction of the arrows;

FIG. 83 is a plan view of the welt tilting mechanism;

FIGS. 84 and 85 are schematic views generally in front elevation of various operating elements of the machine shown in different positions assumed during the operation of the machine;

FIG. 86 is a view in side elevation of various operating elements as seen from the left-hand side of the machine;

FIG. 87 is a view in side elevation of the operating elements of the machine as seen from the right-hand side of the machine;

FIG. 88 is a view in front elevation of the operating elements shown in FIG. 87;

FIG. 89 is a diagrammatic plan view illustrating the path of motion of one of the operating elements;

FIG. 90 is a view in perspective of a shoe prior to its being lasted along its opposite sides and around the toe end thereof in the machine of this invention;

FIG. 91 is a view in section substantially on line XCI—XCI of FIG. 90 and looking in the direction of the arrows;

FIG. 92 is a view in section substantially on line XCII—XCII of FIG. 90 and looking in the direction of the arrows;

FIG. 93 is a view in section substantially on line XCIII—XCIII of FIG. 90 and looking in the direction of the arrows;

FIG. 94 is a plan view of a portion of the shoe as it is being lasted and also showing the operating elements of the machine;

FIGS. 95, 96, 97, 98 and 100 are views in side elevation of the operating elements of the machine and showing the shoe in section, these views showing the operating elements in different positions assumed during the operation of the machine; and

FIGS. 99 and 101 are schematic views in front elevation of the operating elements of the machine and also showing a portion of the shoe.

Referring to the drawings, and especially FIGS. 1, 3 and 4 thereof, the machine therein illustrated is in many respects like the machine shown and described in United States Letters Patent No. 1,796,451, issued March 17, 1931 on an application filed in the name of George Goddu, and thus comprises a head casting 200 on which various operating elements to be described below are supported and within which are contained mechanisms for actuating these elements. This head casting is adjustably supported on the upper end of a column 202 which rises from a hollow base member 204 in which there is contained a drive motor 206, FIG. 1. As is common in

machines of this type, a work table 208 is associated with the column and carried by this table is a switch box 210. The operating elements of the machine, which include upper tensioning grippers, staple forming and driving mechanism, a shoe feeding mechanism, a welt guiding and tilting member and an upper deflector, are actuated by cams associated with two cam blocks, indicated generally by reference characters 212 and 214 mounted on a main drive shaft 216 which is suitably journaled in the head casting, see FIG. 10. The cam block 212 is pinned to the shaft 216 and carries cam tracks for operating the staple forming and driving mechanism and the shoe feeding mechanism, which mechanisms are always in action during the operation of the machine, while the cam block 214 which carries cam tracks for operating the

grippers, welt tilting member and upper deflector, is journaled on the shaft 216 and is adapted to be connected thereto in a manner about to be described when the machine is operating along the sides of the shoe. So far as the staple forming and driving mechanism and the upper tensioning grippers are concerned, the arrange-

ment in the present machine is exactly similar to that in the Goddu machine. Thus, two foot treads 220, 222, FIG. 2, are provided, the first for initiating rotation of the shaft 216, together with cam block 212 which is connected thereto, and the second for causing the cam block 214 to be connected to and driven by the shaft 216.

The motor 206 drives a vertical shaft 224 which carries at its upper end a beveled pinion 226 in mesh with teeth on a clutch member 228 journaled on the shaft 216, FIG. 10. This clutch member forms a part of a clutch and brake mechanism which is constructed exactly like that shown and described in detail in the aforementioned Goddu patent, and which includes an operating member 230, FIG. 4, corresponding to the link 136, see FIG. 5 of the Goddu patent. Therefore, it will be understood that when this operating member is moved to the left, FIGS. 4, 5 and 6, against the resistance of a return spring 232, the brake will be released and the clutch will be engaged so that the shaft 216 is driven in the direction of the arrow, FIG. 4. Upon release of the member 230 to the action of the spring 232, the clutch will be released and a brake member 234, FIG. 10, actuated to bring the shaft to a stop, the arrangement being such that the shaft 216 always completes an integral number of revolutions and is brought to a stop in a predetermined angular position when the member 230 is released.

Referring to FIGS. 4, 5 and 6, the member 230 is connected to one arm 240 of a lever 242 which is rotatably mounted on a shaft 244, journaled in the head casting 200. This lever has another arm 246 which carries a screw 248 adapted to abut a surface 250 on an arm 252, FIGS. 5 and 6. The arm 252 is likewise journaled on the shaft 244 and is acted on by a coil spring 254 which tends to swing it in a counterclockwise direction, FIGS. 4, 5 and 6, to the extent determined by the engagement of another surface 256 thereon with a stop screw 258 threaded into a portion of the head casting 200, FIG. 8. The treadle 220 is connected to the arm 252 by means including a link 260 so that when this treadle is depressed, see FIG. 6, the member 230 will be shifted to the left, thereby causing the shaft 216 to be driven from the motor 206 through the clutch mechanism including the clutch member 228. Upon release of this foot treadle, the parts are returned to the position shown in FIG. 4, thus disconnecting the shaft 216 from the clutch member 228 and causing the brake member 234 to bring the shaft to a stop, FIG. 10.

For connecting the cam block 214 to the shaft 216 a clutch and brake mechanism similar to that disclosed in the above-mentioned Goddu patent is provided, this mechanism including an operating arm 270, FIG. 10, which corresponds to the arm 178 of the Goddu patent, see FIG. 4 thereof. The arm 270 is fast on one end of the shaft 244, and secured to the other end of this shaft is another arm 272, FIGS. 4-8, which is connected to the treadle 222 by means including a link 274 and a yoke member 275. By depressing the treadle 222, thereby swinging the arm 272 in a clockwise direction against the resistance of a return spring 276, FIGS. 4, 5, 6 and 8, the clutch mechanism associated with the cam block 214 will be engaged to cause this cam block to be connected to and driven by the shaft 216, while upon release of the treadle 222 this clutch mechanism will be disengaged and the cam block brought to a stop at a predetermined angular position in the manner explained in detail in the Goddu patent to which reference may be made for details of construction not herein set forth. It will be noted, see FIG. 2, that the treadle 222 overlies the treadle 220. Therefore, when the former is depressed, both the cam blocks 212 and 214 will be rotated, while if treadle 220 is depressed, only the cam block 212 will be rotated.

Secured to the lever 242 is a downwardly extending arm 280 to one side of which there is adjustably fastened a block 282, FIG. 8, provided with a laterally extending abutment 284, FIGS. 4-9. Suspended from the arm 272

by means of a link 286 is one end of an arm 288, the other end of which is secured to a rockshaft 290, journaled in a bracket member 292, supported on the head casting 200. Midway between its ends, this arm carries a downwardly extending member 294, to which there is adjustably secured a latch block 296 having a latch projection 298. When both of the treads 220, 222 are released, the parts assume the positions in which they are shown in FIG. 4, and both cam blocks are stopped in their predetermined angular positions. Now, if the treadle 220 is depressed to engage the clutch for connecting the shaft 216 to the motor 206, the parts assume the positions in which they are shown in FIG. 6 and with the latch projection 298 inserted over the abutment 284 so as to prevent a depression of the other treadle 222 until the treadle 220 has been released. On the other hand, if treadle 222 is depressed, the parts will assume the positions shown in FIG. 5 and both cam blocks will be driven from the motor 206.

The herein illustrated machine has an upper tensioning gripper and gripper operating mechanism which are exactly the same as those disclosed and described in detail in the above-mentioned Goddu patent. Thus the gripper has a fixed jaw 300 and a movable jaw 302 mounted on a body portion 304 which is connected at its upper end to an operating lever indicated generally by the reference character 306 and the outer end of an overdraw rod 308, FIGS. 1, 3, 4, 87 and 88. Associated with the gripper is a jaw closing rod 310, FIG. 4. The cam block 214, FIG. 10, is provided with three cam tracks 312, 314 and 316 corresponding, respectively, to cam tracks 306, 228 and 326 on the cam block 40 of the Goddu patent, see especially FIG. 4 thereof, for imparting gripper closing, updraw and overdraw movements to the gripper by mechanism not shown in detail herein but which is like that disclosed in the Goddu patent. Therefore, when the cam block 214 is connected to the shaft 216, as a result of the depression of the treadle 222, the gripper jaws 300, 302 will first be closed to grip the stock, then moved upwardly and outwardly to tension the stock which has been seized and to draw it outwardly over the bottom of the shoe being lasted in exactly the same manner as is described in the Goddu patent, cam tracks 312, 314 and 316, however, being shaped to provide for gripper movements along paths slightly different from those of the Goddu patent and as illustrated diagrammatically in FIGS. 94 to 101 of the present drawings.

The staple forming and driving mechanism and associated wire feed mechanism are shown more particularly in FIGS. 11-33 of the drawings. Referring first to the staple forming and driving mechanism, this comprises an outside former 400, an inside former 402, and a staple driver 404, see FIG. 16. The outside former is integral with a U-shaped member 406, FIG. 18, which is slidably mounted in a housing 408 secured to one end of a slide 410 by screws 411, FIG. 16. The driver 404 is fastened to an operating member 412 by means of a clamp 413 and screw 415, and this member is slidably received within the member 406, a cover 414 which is secured to the housing 408 by means of screws 416, 416, FIGS. 12, 13 and 14, serving to hold the parts in assembled position. Also formed integrally with the member 406 is a nozzle 418 through which the formed staple "s" is driven by the driver 404. The outside former, adjacent to the nozzle 418, is provided with a groove 420 to receive a guide member 422 having a stepped recess 424 which is adapted to form continuations of the driver passage 426 in the outside former 400, FIG. 15. Attached to this guide member is a plunger 428 which, at times, and as will appear below, is engaged by a cam 430, FIG. 11, to hold the parts in the positions shown in FIG. 15 against the resistance of a leaf spring 432.

The inside former 402 is integral with a member 432 which is slidably mounted in a guideway 434 formed in a portion of the housing 408, FIG. 16. Pivotally mounted

on the housing 408 by means of a pin 436 is an arm 438 having a cylindrical lower end 440 which is received in a similarly shaped recess 442 formed in the member 432. The arm 438 is formed with an inclined camming surface 444 which engages the edge of a recess 446 in the member 406 so that the member 432, together with the inside former 402, will be cammed to the right, FIG. 16, against the resistance of a return spring 448, as the member 432 and outside former 400 are moved downwardly to form the staple "s" from the leading edge of a piece of wire "w" which has previously been fed across the inside former 402, while the members 406 and 412 are elevated, and severed by a knife 450, FIGS. 12, 18 and 21 during an initial portion of the downward movement of the member 406 and outside former 400.

The member 406 on which the outside former 400 is carried is reciprocated in the following manner. Connected to the upper end of the member 406 is a link 452 having at its upper end a slot 460 in which there is received a roll 462, FIGS. 16, 19 and 20. This roll is mounted on the outer end of one arm of a bell-crank lever 464 having another arm which carries a cam roll 466, FIG. 23, and a smaller roll 468, see FIG. 21. The bell-crank lever 464 is pivotally mounted on the head casting 200 by means of a screw stud 470 with the roll 466 in alignment with a peripheral cam track 472 formed on the cam block 212, see FIG. 10. A spring 474, FIGS. 11, 19 and 20, is arranged to hold the roll 466 yieldingly against the cam track 472. Secured to the cam block 212, in the immediate vicinity of a drop "a" in the cam track 472, FIG. 23, is a member 473 formed with a curved lip 474 facing toward the cam track 472. This lip is spaced from the cam track 472 in such a way as to engage the small roll 468 on the bell-crank lever 464 as the cam roll 466 rides down the drop "a," thus, in effect, producing a positive closed cam action on the lever 464 when the member 406 and inside former 400 are being moved downwardly to sever the wire "w" from which the staple "s" is formed and to form the staple from this severed portion of the wire.

The slide 410, on which the housing 408 is mounted, is reciprocated by means of a cam track 480, formed in the cam block 212 and in this cam track there is received a cam roll 482 carried on the upper end of this slide, FIG. 11. For operating the driver 404, there is provided a coil spring 490, FIG. 12, which is adjustably connected to a driver operating arm 492 rotatably mounted on a stud shaft 493 which is secured to an upwardly projecting portion 494 of the slide 410 by means of a nut 496, FIG. 16. The arm 492 has formed integrally therewith a latch abutment 498 adapted to be engaged by a latch member 500 which is pivotally mounted on one arm of a latch operating lever 502, FIGS. 19 and 20. Mounted on the other arm of this lever is a cam roll 504 which is received within a cam groove 506 formed in the cam block 212, see also FIG. 10. A coil spring 508 tends to swing the latch member 500 in a counterclockwise direction, thereby to hold its operating end 510 yieldingly in engagement with the latch abutment 498. Pivotally mounted on the slide 410 there is a supplemental latch member 512 having a latch portion 514 and an operating arm 516 in which there is threaded an adjustable abutment screw 518.

The driver operating arm 492 is connected to the driver operating member 412 by means of two links 520, 522 and a lever 524 which is pivotally mounted on the upper end of a standard 526 secured to a forwardly extending portion of the slide 410, FIGS. 19 and 20. Carried by the lever 524 is a member 530 having an offset abutment portion 532 which, after the staple has been driven, lies directly over a similar offset abutment 534 on a member 536 carried by one arm of the lever 464, FIG. 19. During the remainder of the operating cycle and an early portion of the next operating cycle, the lever 464 is swung in a counterclockwise direction by the cam 472,

FIG. 23, and by the interaction of these two abutments the lever 524 is swung in a clockwise direction. In this way, the driver operating arm 492 is likewise swung in a clockwise direction so that the operating end 510 of the latch member 500 may reengage the latch abutment 498 when the slide 410 has been withdrawn to the position shown in FIG. 19 by the cam 480, FIG. 11. As the operating cycle continues, the lever 464 is swung further in a counterclockwise direction by the cam 472 thereby to elevate the member 406 and inside former 400 to their uppermost positions and the slide 410 is moved forwardly thereby further cocking the driver operating spring 490 and elevating the driver 404 to its uppermost position.

A length of wire "w" is now fed across beneath the outside former 400 and over the inside former 402 by mechanism about to be described, whereupon the cam roll 466 rides down the drop "a" on the cam 472, under the positive control of the lip 473 and small roll 468, FIG. 23, so that the outside former is moved downwardly to sever a piece of wire and to form it into a staple. Immediately thereafter, the lever 502 is rocked in a counterclockwise direction by the cam 506 to bring the upper end of the latch member 500 into engagement with a latch tripping screw 540, carried by the slide 410. As the operating end 510 of this latch member is thus disengaged from the latch abutment 498, this abutment is immediately engaged by the operating end 514 of the supplemental latch 512. Continued movement of the lever 502, however, soon causes the operating end 510 of the latch member 500 to engage the abutment screw 518, FIG. 20, on the arm 516 of the supplemental latch 512, thus to swing this latch in a counterclockwise direction and to cause its operating end 514 to release the arm 492 to the action of the operating spring for driving the staple "s."

For severing the piece of wire from the length of wire "w" which is fed across the inside former and below the outside former during each cycle of operations of the staple forming and driving mechanism, there is secured to the member 406, which carries the outside former 400, a block 550 to which the wire severing knife 450, FIGS. 18 and 21, is connected. As shown in these figures, this knife has a laterally extending upper portion 552 which is slidably received within a guideway 554 formed in the block 550 and is of dovetail shape so as to fit in a corresponding guideway 556 formed in a block 558. The latter block is secured by a screw 560 to a slide 562 which is mounted in a guideway 564 associated with a portion of the housing 408 and cover 414. This slide is provided with a passageway 566 through which the wire "w" is fed by a feed mechanism about to be described through a flexible tube 568. As has been suggested above, in operating around the toe end of a shoe a longer staple will be required than when operating along the opposite sides of the shoe from tip line to breast line. To provide for such a longer staple, the wire feeding mechanism is set to feed a corresponding longer length of wire during each feeding cycle, and in order that the legs of the staple will remain of equal but longer length, the slide 562 is shifted to the left by an amount equal to one-half of the increase in the length of the wire which is fed. As shown in FIG. 21, the slide 562, as well as the wire feeding mechanism, are set for such a longer staple.

In general, the wire feeding mechanism of the herein illustrated machine is similar to that disclosed in the Goddu patent mentioned above. As in this prior arrangement, the wire is fed by mechanism including a feed wheel 600, FIG. 3, which is rotated intermittently by means of a pawl 602 actuated by a link 604, FIGS. 21 and 22. At its lower end the link 604 is connected by means of a stud 606 and nut 608 to a member 610, FIGS. 32 and 33, which carries two anti-friction rolls 612, 612, FIG. 29. These rolls are received within an arcuate

slot 614 formed in one arm 616 of a cam lever 618. The other arm 620 of this lever carries a cam roll 622, FIG. 21, which is yieldingly held against a side cam 624 by means of a spring 626, FIG. 22, which tends to rotate the lever 618 in a counterclockwise direction, FIG. 21. As will be apparent, the wire feed wheel 600 will be turned through a small angle during each complete revolution of the shaft 216 to which the cam 624 is secured.

Also, the magnitude of the angle through which the feed wheel 600 is turned, and thus the length of the wire which is fed, may be varied by shifting the member 610, relatively to arm 616 of the lever 618 to vary the effective length of arm 616. For thus shifting the member 610 the following arrangement is provided.

Extending downwardly from the member 610 is a post 623 on the lower end of which there is rotatably mounted a barrel-shaped roll 629. Slidably mounted in a guideway 630 on the supporting bracket which is indicated generally by the reference character 632 and which is supported on the head casting 200 is a carriage 634, FIGS. 21, 22, 28, 30 and 31. Secured to this carriage for angular adjustment thereon by means of a screw stud 636 and a clamp screw 638 is a housing 639. This housing carries two cam plates 640 and 642, having angular cam surfaces 644, 646, and these plates are adjustably secured to the housing, respectively, by clamp screws 648 and 650, FIGS. 30 and 31. Formed integrally with the carriage 634 is an upstanding post 652 on the top of which there is pivotally mounted a latch plate 654 which is provided with a latch shoulder 656, FIGS. 32 and 33. A compression spring 658 yieldingly urges this latch plate in a counterclockwise direction to the extent permitted by an ear 660 which engages the post 652.

Pinned to the shaft 244 which carries the operating arm 270 for the clutch mechanism associated with the cam block 214, mentioned above, is another arm 662 which is connected to the post 652 by means of a link 664, FIG. 22. With this arrangement, when the treadle 222, FIG. 2, is depressed to effect operation of the grippers by connecting the cam block 214 to the shaft 216, FIG. 10, the carriage 634 and parts mounted thereon will be shifted to the left, FIG. 22, and upwardly, FIG. 31, as the result of angular movement of the shaft 244 in the direction of the arrow on FIG. 22. At all other times, the shaft 244, as well as the carriage 634, will remain in the position shown in FIG. 22, and with the carriage 634 in the position shown in FIG. 31.

Pivotedly mounted on the member 610 by means of a rockshaft 670, to which it is secured, is a pawl 672 having formed integrally therewith a downwardly extending latch arm 674, FIGS. 22, 28, 32 and 33. A compression spring 676, FIG. 28, is arranged to hold the pawl yieldingly in engagement with teeth 678 formed on the arm 616, FIG. 29, thereby to hold the member 610 against movement relatively thereto. Adjacent to the left-hand end of the latch shoulder 656 the latch plate 654 is cut away, as indicated at 680, FIGS. 30-33, to provide a clearance space for the latch arm 674 when the cam lever 618 is rocked in a clockwise direction, FIG. 21, by the cam 624, the latch arm moving downwardly in an arcuate path, as will be apparent in FIG. 21. Also secured to the shaft 670 is an angularly shaped arm 682 having on its outer end an inclined cam surface 684 adapted at times to cooperate with an oppositely directed and inclined cam surface 686 formed on a lateral extension 688 of the latch plate 654. The shape of the arm 682 is such, see FIGS. 22 and 31, that when the carriage 634 is in the position shown in these figures, the arm 682 will clear the extension 688 in all positions of the lever arm 618. On the other hand, when the carriage is moved to the position shown in FIGS. 30 and 33, as a result of the depression of the treadle 222, the cam surfaces 684 and 686 will be brought into alinement. Because of their oppositely disposed inclinations, these surfaces are adapted to clear each other as the arm 618

is swung downwardly carrying with it the member 610. However, when the carriage 634 is returned to the position shown in FIG. 31, as the result of movement downwardly, as viewed in FIG. 30, or to the right as viewed in FIG. 33, the surface 686 will act on the surface 684 to swing the arm 682 in a clockwise direction, thereby moving the pawl 672 out of engagement with the teeth 678 on the arm 616.

Referring to FIGS. 30 and 31, it will be seen that during movement of the carriage 634 upwardly from the position of FIG. 31 to the position of FIG. 30, the member 610 will be swung in a clockwise direction, FIG. 21, by the action of cam surface 644 on the roll 629, after an initial lost motion which permits the pawl 672 to be withdrawn from the teeth 678 by the action of the latch arm 674 and latch shoulder 656, see FIG. 32, and held withdrawn until the movement of member 610 is completed. Now, as movement of the carriage is continued, latch arm 674 will snap over the shoulder 656 to permit pawl 672 to return to locking position. Similarly, when the carriage 634 is moved in the opposite direction, i.e., from the position shown in FIG. 30 to the position shown in FIG. 31, the member 610 will be swung in a counterclockwise direction, FIG. 21, by the action of cam surface 646, after an initial lost motion which permits the cam surface 686 to act on the surface 684 to release the pawl 672, and to hold it released until member 610 has been returned to the position shown in FIG. 21. Now, as carriage 634 returns to the position shown in FIGS. 22 and 31, the latch plate 654 is cammed downwardly by the latch arm 674 and the parts assume the positions shown in FIGS. 22 and 32. It will be understood that these movements of the carriage 634 occur only at a time when the arm 616 of the lever 618 is in the position shown in FIGS. 21, 22, 29 and 32.

From the foregoing, it will be understood that when the treadle 222 is depressed for the purpose of rendering the gripper operative, the carriage 634 will be moved to the position shown in FIG. 30 and the member 610 will be moved toward the axis of oscillation of the bell-crank lever 618, from the position in which it is shown in FIG. 21, thereby setting the wire feeding mechanism for the feeding of a shorter length of wire. At the same time, the knife 450 is moved to the right an appropriate amount to provide for the shorter staple, i.e., an amount equal to one-half of the difference between the longer length of wire and the shorter length of wire. This movement is imparted to the knife 450 by the member 610 as it is moved to decrease the length of the piece of wire which is fed. Referring again to FIG. 21, the slide 562, to which the block 558 which guides the knife 450 is secured, is provided with two upstanding ears 700, 700 between which there is received the ball-shaped end 702 of a stud 704. This stud extends downwardly from a block 706 which is secured to the lower end of a shaft 710, see also FIG. 22. This shaft is journaled in a bearing bracket 712, FIGS. 25 and 26, mounted on a support 714 which is carried by the housing 408, FIG. 22. On the upper end of the shaft 710 there is mounted a block 716 from which there projects a stud 718 having a ball-shaped end 720. This ball-shaped end is received between two ears 722, 722, FIG. 21, formed on an arm 724 which is secured to one end of a slide 726, see also FIGS. 22, and 24-28.

The slide 726 is mounted for reciprocation in a guideway 728 which is formed in a cover plate 730 secured to a supporting plate 732, mounted on a part of the head casting 200, FIGS. 21, 24 and 26. Carried by the other end of this slide is a bearing bracket 740 in which there is journaled a shaft 742 and just beyond this bearing bracket there is a vertically disposed slot 744 in the slide, FIGS. 21, 22, 24 and 28. At its upper end, the member 610 is angularly offset, FIGS. 22 and 28, and carries a headed pin 750, slidably within a bore in the

member 610. A leaf spring 752, which engages the headed end of this pin, yieldingly holds it in the position shown in FIG. 22, in which position the pin projects into the slot 744 in the slide 726 in which it nicely fits. With the pin in this position, the member 610 is connected to the slide and thus, when the member 610 is shifted to the left, FIG. 21, as the treadle 222 is depressed to render the gripper operative and to provide for the shorter staple, the slide 726 will also be shifted to the left, FIGS. 21 and 24. As a result of such movement of the slide 726, the slide 562 will be shifted to the right, in a manner which will be apparent, and the studs 704 and 718 are so proportioned in length that the slide 562 moves a distance equal to one-half of the amount that the wire feed is shortened. The shifting of the member 610 to and from its two different positions relatively to the arm 616, FIG. 21, occurs only when the arm 616 is in the position shown in FIG. 21, which it occupies at the end of each complete revolution of the shaft 216.

During oscillation of the arm 616 to effect the feeding of a length of wire to the staple forming and driving mechanism, the member 610 is disconnected from the slide 726 in the following manner. Secured to one end of the shaft 742 there is an arm 760 which, together with a collar 762, holds this shaft against axial movement relatively to the bearing bracket 740, FIGS. 21 and 24. At its upper end, the arm 760 carries a cylindrical projection 764 which is slightly smaller in diameter than the pin 750 and of a length just slightly greater than the thickness of the slide 726, this cylindrical projection being in alignment with the slot 744 in the slide 726. The shaft 742 extends through a guide bearing 766 and at its other end has secured thereto an elongated collar 768 which is provided with a downwardly extending tooth 770, FIGS. 23 and 24. This tooth is received within a correspondingly shaped notch 772 formed in the upper end of an arm 774 which extends upwardly from a shaft 776. This shaft is journaled in a bearing bracket 778, mounted on the supporting plate 732, and carries another and longer upstanding arm 780, FIG. 24. At its upper end, the arm 780 has an offset portion, see FIGS. 21 and 23, which is in alignment with a projection 782 formed on one arm of the outside former operating lever 464, see also FIG. 23. Thus, at the beginning of each revolution of the shaft 216, as lever 464 is rocked in a counterclockwise direction, the arms 780 and 774 will be rocked in a clockwise direction, while the arm 760 will be rocked in a counterclockwise direction, FIGS. 22 and 28, thereby causing the projection 764 to push the pin 750 out of the slot 744 in the slide 726. Also, the upper end of the arm 760 will exert pressure against the left-hand end of the slide, as viewed in FIGS. 21 and 24, thereby binding this slide against movement along the guideway 728. Now, as the arm 616 is oscillated during the feeding of the wire, the end of the pin 750 will slide upwardly and downwardly on the end of the projection 764 and on the rear face of the slide 726, FIG. 28.

It will be understood that shortly after the shaft 216 commences each revolution, the slide 410 which carries the staple forming and driving mechanism, including, of course, the housing 408, moves downwardly and to the right, FIGS. 19, 20 and 22. During such movement of the slide 410 the wire feeding mechanism is operated, the appropriate length of wire is severed by the knife 450, and then formed into a staple in the manner explained above. As the slide 410 moves in this direction, away from the position shown in FIG. 22, the ball end 720 on the stud 718 moves along between the ears 722, 722. The staple is formed as the roll 466 rides down the drop "a" on the cam 472, FIG. 23, and the lever 464 will come back to its original position, thus permitting the pin 750 to be reinserted into the slot 744 and the slide 726 by spring 752, the member 610 having by this time, of course, been returned to the position shown in FIGS. 22 and 28.

As the slide 410 moves downwardly and to the right, FIG. 22, for the operation of the staple forming and driving mechanism, the slide 726 is additionally locked against movement along the guideway 724 in the following manner. Secured to one side of the bracket 712 there is another bracket 790 which carries oppositely facing plates 792, 792 provided with inclined cam surfaces 794, 794, FIG. 25. Pivotally mounted, by means of a pin 796 on the cover plate 730, are two friction pawls 798, 798, FIG. 27. A compression spring 800 is arranged to swing these pawls in opposite directions and thus to cause them to grip the slide 726, as shown in FIG. 27. When the slide 410 is in its retracted position, FIG. 22, the cam surfaces 794, 794 engage and thus release these pawls, see FIGS. 22 and 25. However, shortly after the slide 410 starts to move away from its retracted position, these cam surfaces will also move away from the pawls and thus release them to the action of the spring 800, which actuates the pawls to clamp the slide in the manner just explained. This clamping action continues until just before the slide 410 completes its return movement. Therefore, after the slide 562, FIG. 21, which carries the wire severing knife 450, has been shifted to one or the other of its two positions, it is securely held in that position during operation of the staple forming and driving mechanism. This slide is, however, released for movement at the end of each operating cycle, i.e., at the end of each complete revolution of the shaft 216.

During the operation of the machine, the shoe being lasted, which is herein illustrated as including upper materials, indicated generally by the reference character U, assembled on a last L, together with an insole I provided with a so-called flat rib R, is located in a heightwise direction, relatively to the operating instrumentalities, by means of a shoe rest 810, and is guided laterally by an anvil 812 which is received within the space beneath the rib, see FIGS. 34, 39, 40, 94-101. The shoe rest 810, which to facilitate movement of the shoe is provided with an anti-friction ball 814, and the anvil 812, FIGS. 39 and 40, are secured to the lower end of a post 818, FIG. 35, carried by a slide 820, FIG. 38. This slide is mounted in a guideway 822 formed in a housing indicated generally by the reference character 824, FIG. 35, which is secured to a bracket 826 that projects outwardly from a portion of the head casting 200, FIG. 36. The post and, of course, the parts carried thereby, are held yieldingly in the position shown in FIG. 38 and against an adjustable stop screw 828 by means of a compression spring 830 contained within the slide 820, the tension of which may be varied by an adjusting screw 832, and a plunger 834.

Secured to the lower end of the post 818, by means of screws 840, 840 and two clamp screws 842, 842, is a bracket 844 in which there is formed a guideway 846, FIGS. 34, 35, 37, 95 and 96. Slidably mounted for reciprocating movement in this guideway is the outer end portion 850 of an auxiliary support or guide 852 which is adapted to be projected from the inoperative position in which it is shown in FIGS. 34, 94 and 95 to the operative position in which it is shown in FIGS. 96-98 and 100. The function of this auxiliary support or guide is to engage the inside of the insole rib R in a location adjacent to the anvil 812 and substantially in line with the direction of the pull applied on the upper materials by the gripper jaws 300, 302, thereby to obviate or at least reduce to a minimum any tendency for the force exerted on the upper materials by the gripper jaws to swing the shoe about the fulcrum point provided by the anvil 812 which, as will appear in FIG. 94, is offset some distance to the left of the line of action of the gripper jaws. During the feeding movements of the shoe, which are effected by mechanism about to be described, the auxiliary support or guide 852 is withdrawn to its inoperative position, thus to facilitate the feeding of the shoe, by the reduction of the friction on the rib, as well as the turn-

ing of the shoe by the operator about the anvil as a fulcrum to maintain the shoe in the desired position relatively to the operating instrumentalities of the machine. For moving the auxiliary support to and from these positions at the proper time in the operating cycle of the machine, the following arrangement is provided.

Extending outwardly from the end portion 850 of the auxiliary support 852 there is a pin 860 which projects through a slot 862 formed in the lower end of a member 864, FIGS. 34, 95 and 96. This member is secured to and actually forms a part of a lever 866 which is fulcrumed on a pin 868 carried by a bracket 870 which is secured to the housing 824, FIGS. 34, 35 and 36. Carried on the upper end of this lever 866 are a bearing block 872 and an angularly disposed arm 874, FIGS. 34, 44, 45 and 48. The arm 874 is channel-shaped and has pivotally mounted thereon, by means of a pin 875, a latch member 876, see also FIG. 47. Secured to one side of the member 876 is a cam block 878 which is provided with oppositely facing parallel cam surfaces 880, 882, see especially FIG. 46. Pivotally mounted on the latch member 876 by means of a pin 884 is a latch point 886, FIG. 47, which is yieldingly held in the solid line position in which it is shown in that figure by means of a tension spring 888. The member 536, which is carried by the outside former operating lever 464, referred to above, and shown in FIGS. 19 and 20, has a point 890 which is adapted to engage the latch point 886 when the latch member 876 is swung to the dotted line position indicated in FIG. 44, and to swing the lever 866 in a counter-clockwise direction against the resistance of a coil spring 892, FIG. 34, thereby projecting the auxiliary support 852 to its operating position, see FIGS. 96, 97, 98 and 100, as the operating lever 464 is moved in a counter-clockwise direction, FIGS. 19 and 20, by its associated cam early in each operating cycle and prior to the operation of the gripper jaws 300, 302. The lever 866 is held in this position by a latch arm 894 having an inclined operating surface 896 which is moved into engagement with a latch plate 898 by means of a spring 900 and to the extent permitted by an adjustable stop member 902, FIGS. 52 and 53. The latch arm 894 is mounted on one end of a rockshaft 904 which is journaled in the aforementioned bearing block 872 and carries on its opposite end a trip arm 906, FIGS. 34, 35, 44, 45 and 48.

Pivotally mounted on the head casting 200, by means of a screw stud 910, there is an elongated lever 912 which at one end is connected, by means of a link 914, to the lever 272 which, as pointed out above, is associated with the treadle 222, FIGS. 1 and 2, and see also FIGS. 4, 5 and 6. Secured to the other end of this lever there are two cam blocks 920 and 922, see especially FIGS. 41, 42 and 43. The cam block 920 is shaped to provide an inclined cam surface 930 which is parallel to the cam surface 882 on the cam block 878, see FIG. 49, while the cam block 922 is shaped to provide an inclined cam surface 932 which is parallel to the cam surface 880 on block 878, see FIG. 51. When the treadle 222 is depressed, in order to set the gripper into operation, the left-hand end of the lever 912 will be elevated from the position shown in FIGS. 34 and 49 to the position shown in FIGS. 48 and 50. As a result of such upward movement of this end of the lever 912, the lever 866 will be rocked in a counterclockwise direction, from the position shown in FIG. 34 to the position shown in FIG. 48, see also FIG. 50, whereupon the latch arm 894 will be moved to its latching position, FIGS. 52 and 53, by the spring 900. Also, the latch member 876 will be swung to the dotted-line position shown in FIG. 44 (solid line position in FIG. 50) by the action of the cam surface 932 on the cam surface 880. Upon release of the treadle 222, the left-hand end of the lever 912 will be returned to the position shown in FIG. 34, see also FIG. 51, while the lever 866 will be held in the position shown in FIG. 48 by the latch arm 894 with the auxiliary support 852 projected to its

operative position, see FIGS. 96, 97, 98 and 100. Also, as the left-hand end of the lever 912 moves downwardly to the position in which it is shown in FIG. 51, the latch member 876 will be returned to the solid line position in which it is shown in the last-mentioned figure and also in FIG. 44 by the action of the cam surface 930 upon the cam surface 882.

The driver operating arm 492, see FIGS. 4, 11, 12 and 19, carries a trip block 940 which is adapted to strike the trip arm 906 and thus move the latch arm 894 in a clockwise direction, FIG. 52, to release the lever 866 to the action of the spring 892, as each staple is driven, thus permitting the lever 866 to be returned to the position shown in FIG. 34 by the spring 892 and the auxiliary support 852 to be retracted to its inoperative position, see FIG. 34. However, if the operator holds the treadle 222 depressed for another operating cycle of the gripper, the latch member 876 will remain in the dotted line position shown in FIG. 44, the lever 866 will be swung back to the position shown in FIG. 48, and the auxiliary support 852 will be projected to its operative position by the action of the point 890 carried by the inside formed operating member 464, on the latch point 886. In other words, when the treadle 222 is depressed to effect operation of the gripper, the auxiliary support 852 is projected to its operative position and held in such position during the operation of the gripper and until the staple is driven, whereupon this auxiliary support is immediately retracted to its inoperative position to facilitate the feeding of the shoe. Early in the next operating cycle, as the outside former is being elevated, the auxiliary support will again be projected and latched in its operative position prior to the operation of the gripper. On the other hand, when treadle 220 is depressed, thereby discontinuing the operation of the gripper but continuing the operation of the staple forming and driving mechanism, the lever 912 will be returned to the position shown in FIG. 34 by spring 276, see FIG. 8, so that the latch member 876 assumes the solid-line position shown in FIGS. 44 and 45, due to the action of the cam surface 930 on the cam surface 882 in which position the point 890, associated with the outside former operating member, clears the latch point 886. Thus the lever 866 remains in the position shown in FIG. 34 with the auxiliary support 852 retracted to its inoperative position.

Referring to FIG. 53, as previously mentioned the operating surface of the latch arm 894 is inclined. Also, the extent of movement of this latch arm 894 by the spring 900 may be varied by suitable adjustment of the stop member 902. As will be apparent, the exact location of the auxiliary support 852, when it is projected to its operative position, will be determined by the adjustment of the member 902. Thus, by suitable adjustment of the member 902, the auxiliary support may be caused to assume different locations relative to the anvil 812 when it is in its operative position.

During each operating cycle of the machine, as the slide 410 which carries the staple forming and driving mechanism is retracted, subsequently to the driving of a staple, the shoe is fed along by means of a feed gripper which takes a hold of the welt W and then moves to the left to the position shown in FIG. 94. This feed gripper comprises a lower jaw 1000 having a substantially flat surface 1002, FIG. 62, for engaging the top side of the welt and an upper jaw 1004, provided with an annular edge 1006, FIG. 61, for engaging the underneath side of the welt which is, of course, uppermost as a shoe is presented to the subject machine, FIGS. 62 and 94. The lower jaw 1000 is pivotally mounted by means of a pin 1038 on one end of a table 1010 which in turn is supported on a platform 1012 for swinging movement about a pin 1014, FIGS. 54 and 56. As will appear from an inspection of FIG. 62, swinging movement of the lower jaw 1000 is limited by engagement of a por-

tion of this jaw with the table 1010. The upper jaw 1004 is pivotally mounted, by means of a pin 1016, on a block 1018, FIG. 60, which block is secured to and forms a part of a lever 1020 fulcrumed on the aforementioned pin 1008. The platform 1012 is carried by and extends forwardly from a C-shaped supporting member 1022, FIGS. 57 and 59, which in turn is fastened to an intermediate bracket 1024 associated with the head casting 200, see also FIG. 67.

Secured to and extending upwardly adjacent to one side of the platform 1012 is a post 1026 on which there is pivotally mounted by means of a pin 1028 an arm 1030 having an offset lower end 1032, FIG. 54. Rotatably mounted on this offset lower end of the arm 1030 is a roller 1034 which is received within a cam track 1036 formed partly in the table 1010 and in a top plate 1038 secured thereon by screws 1040, FIGS. 55 and 58. This arm 1030 is connected by means of a link 1042, FIGS. 11, 56 and 62, to a bracket member 1044, FIGS. 19, 20 and 62, which is carried by the slide 410 and housing 408. As will be apparent, when the slide 410 is withdrawn after the driving of a staple, the roller 1034 will move from the position in which it is shown in FIG. 58 to the position shown in FIGS. 54, 56 and 62, thereby swinging the table 1010 in a clockwise direction, as viewed from above, FIGS. 54 and 58, and moving the jaws 1000 and 1004 from the right (dotted-line position) to the left (solid-line position) FIGS. 63, 83 and 94. During such movement of these jaws they are closed on the welt W in the following manner.

Fastened to and extending laterally from one end of the lever 1020 is a block 1050 having a lower edge face 1052, FIGS. 59 and 62. Slidably received within a guideway 1054 formed in the top plate 1038 is a slide 1056, FIGS. 55 and 58 having an upwardly projecting portion 1058 which is provided on its upper end with an inclined camming surface 1060 and a flat surface 1062, see FIG. 56. When the slide 1056 is moved to the left, FIG. 56, and to the right, FIG. 62, the inclined surface 1060 will first engage the lower face 1052 of the block 1050 thereby moving the jaw 1004 toward the jaw 1000 to grip the welt W, after which the flat surface 1062 will engage the surface 1052 to hold the jaws in welt gripping position. Slidably mounted in a guideway 1070 formed in a cover plate 1072, secured to the post 1026, FIG. 62, is an actuating slide 1074 which at one end is shaped to provide an open recess 1076 within which the portion 1058 of the slide 1056 is received, FIG. 54. This actuating slide also carries adjustable abutment screws 1080, 1082 which are in alignment with the arm 1030.

With the arrangement which has just been described, when the slide 410 is retracted, after the driving of a staple, the arm 1030 will be swung from the position shown in FIG. 58 to the position shown in FIGS. 54, 56 and 62, thereby swinging the table 1010 in a direction to cause the jaws 1000 and 1004 to move from the dotted line position to the solid line position in FIGS. 63, 83 and 94. At the beginning of such swinging movement of the table 1010, the jaws 1000 and 1004 will be closed on the welt W as a result of the previous forward movement of the slide 410, and movement of the arm 1030 to the position shown in FIG. 58, and by the action of the projection 1058 on the block 1050. However, before this swinging movement of the table is completed, arm 1030 will strike the abutment screw 1082 and move the slide 1056 to the right, FIGS. 54 and 56, and to the left, FIG. 62, thereby causing the jaws 1000 and 1004 to release their grip on the welt. Now, when the slide 410 is advanced during the next operating cycle, the arm 1030 will be swung in a clockwise direction, FIG. 56, and the table 1010 in a counterclockwise direction, FIG. 54 to the position shown in FIG. 58. Before this movement of the arm 1030 is completed, the roller 1034 carried thereby reaches a portion of the cam track 1036 which is parallel to the

direction of the movement of the slide 1056 so that movement of the table is terminated. As the arm 1030 completes its swinging movement, it engages the abutment screw 1080 and moves the slide 1074 in a direction to effect the closing of the jaws 1000 and 1004 on the welt.

Referring to FIGS. 56 and 62, it will be noted that the welt W is gripped between the flat surface 1002 on the jaw 1000, which engages the top or finished side of the welt and the sharpened annular ridge 1006 of the jaw 1004 which embeds itself into the bottom or flesh side of the welt. Thus, a very secure grip is provided which insures positive feeding of the shoe to which the welt is attached. However, because of the circular shape of the ridge 1006 on the jaw 1004, see especially FIG. 61, and the relative smooth surface 1002 on the jaw 1000, the welt, and hence the shoe to which it is attached, may be readily swung about an axis normal to the welt and centered in the circular ridge 1006, by the operator during the feeding of the shoe, to maintain the curved edge of the shoe bottom always in proper position with respect to the various operating instrumentalities of the machine. Moreover, inasmuch as the surface 1002 of the jaw 1000 which engages the top of the finished side of the welt is very smooth, there is no danger of marking or otherwise marring this surface.

The welt W which is stored on a reel, not shown, is led to the point of operation by means of two flanged guide rollers 1100, 1102, FIG. 3, a supporting roller 1104, FIGS. 34, 35, 83-85, and a welt guide 1106, FIGS. 65, 66, 83-86, 94-96, 98, 99 and 101. The welt guide 1106 which is formed from a short portion of a flattened rectangular tube is secured to an arm 1108 formed integrally with a rockshaft 1110, FIGS. 65 and 70. This shaft is journaled in a bracket 1112 which in turn is connected to another bracket 1114 secured to one arm of a lever 1116, FIGS. 65 and 66. The shaft 1110 is held against axial movement in one direction by means of an abutment member 1118 which is secured to the bracket 1112, FIG. 65, and fast on this shaft is an operating arm 1120, see also FIG. 70. A coil spring 1122, which surrounds one end of the shaft 1110, tends to hold this shaft, arm 1120 and the welt guide 1106 yieldingly in the positions shown in FIGS. 65, 66, 69, 83 and 84. For the purpose of facilitating the engagement of the upper materials U by the gripper jaws 300, 302, the welt guide 1106 is turned to the position in which it is shown in FIGS. 85, 88, 96, 99 and 101, thereby swinging the welt W upwardly, out of the way of the gripper jaws, by means of mechanism about to be described. Lever 1116 is pivotally mounted on the bracket 1024, which is mounted on a portion of the head casting 200, by means of a stud 1130, FIGS. 65, 67 and 68, and is yieldingly held in the position shown in FIG. 66 by means of a tension spring 1132 and as determined by the engagement of a portion of the lever with an abutment surface 1134 associated with the head casting, FIG. 68.

Secured to and extending downwardly from the bracket 826, FIG. 34, is a bar 1140 on which the welt supporting roller 1104 is supported. Mounted on this bar is another bracket 1142 to which there is secured a plate 1148, see also FIGS. 70, 71 and 72. This plate has a laterally extending portion 1150, FIG. 72, which is provided with a bore 1152, FIG. 79, and has fastened to its lower portion two other plates 1154 and 1156, FIG. 70, this latter plate being provided with a bore 1158 which is in axial alignment with the bore 1152. The plate 1154 has a rearwardly extending portion 1160 to which there is secured a split block 1162 having a bore 1164 within which there is clamped, by means of a binding screw 1166, a bushing 1168, FIG. 73. This bushing is provided with a bore 1170 and a flange 1172 in which there is a groove 1174, FIGS. 73 and 74. Journaled in the bores 1152, 1158 and 1170 is a shaft 1180 provided with an annular groove 1182, a radial flange 1184, and a flattened end portion 1186, FIGS. 75, 76 and 77. As is shown in these three figures, the flange 1184 is machined to present

oppositely facing ribs 1188 and 1190. Fitted over the flattened end portion 1186 of the shaft 1180, and thus non-rotatably mounted thereon, is a member 1192, FIG. 82, to which there is adjustably secured, by means of a screw 1194, an operating finger 1196, FIGS. 70, 71 and 79. As will presently appear, the finger 1196 is adapted to engage the operating arm 1200 and to swing that arm in a counterclockwise direction, FIG. 70, thereby to move the welt guide from the position shown in FIGS. 65, 66 and 84 to the position shown in FIGS. 85, 88, 96, 99 and 101.

Rotatably mounted on the shaft 1180, between the portion 1150 of the plate 1148 and the flange 1172 of the bushing 1168, is an arm 1200, FIG. 79, which is shaped as shown in FIG. 81 to provide an arcuate surface 1202 and a groove 1204. A thrust member 1206, FIG. 80, which is secured to the block 1162 by means of a laterally extending portion 1208, see FIG. 72, is provided with a bore 1210 to receive the flange 1184 of the shaft 1180, FIG. 79, and supports the arm 1200 against movement axially of the shaft 1180. As will be apparent, when the shaft 1180 is in the position shown in FIG. 79, the rib 1188 of the flange 1184 will be received within the groove 1174 on the bushing 1168 thereby locking the shaft 1180 and the operating finger 1196 in the angular positions in which they are shown in FIG. 70. On the other hand, when the shaft 1180 is shifted to the right from the position shown in FIG. 79 and by mechanism about to be described, rib 1190 will enter the groove 1204 so that the arm 1200 will be connected to the shaft 1180 and this shaft at the same time will be released for rotation with the arm 1200. This arm is oscillated in a clockwise direction, as viewed in FIG. 70, counterclockwise direction, as viewed in FIG. 81, by mechanism about to be described. Referring to FIGS. 11 and 12, there is carried by the outside former 400, a bracket 1210 to which there is secured a member 1212 provided with a spherically-shaped groove 1214 adapted to receive the ball-like end 1216 of a rocker arm 1218, see FIG. 81. This rocker arm is slidably mounted in a trunnion block 1220 which is pivotally mounted, by means of an integrally formed stud bolt 1222, on a bar 1224 carried by the plate 1148, FIGS. 70, 71 and 72. Secured to the other end of this rocker arm is a striker block 1226. A coil spring 1228, stretched between this block and the arm 1200, tends to hold the arm in the position shown in FIG. 81, and with a stop member 1230, FIG. 70, carried by the arm in engagement with the edge of the plate 1148.

The groove 1214 in the member 1212, FIG. 11, is inclined at the same angle as the guideways for the slide 410. Thus, during reciprocating movements of this slide, the rocker arm 1218 will be held in a fixed position. At the beginning of each operating cycle, the outside former 400 occupies its lowermost position, and in FIGS. 70 and 81 the member 1212 is shown in its corresponding lowermost position. During an initial stage in the operating cycle, the outside former is elevated by means of the cam 472 and hence the member 1212 is moved upwardly, see arrows, FIGS. 70 and 81. As a result of such upward movement of the member 1212 the rocker arm 1218 will be swung in a clockwise direction, FIG. 70, counterclockwise direction, FIG. 81, and by the action of the striker block 1226 on the surface 1202, arm 1200 will be swung in the same direction. Now, if the shaft 1180 is shifted to the right, FIG. 79, so that the flange 1184 on the shaft 1180 is connected to the arm 1200, the operating finger 1196 will be swung in a clockwise direction, FIG. 70, thereby moving the welt guide 1106 to the position shown in FIGS. 85, 86, 88, 96, 98 and 99. When the outside former is moved downwardly, the parts just mentioned will be returned to their original positions. However, before this occurs during the operating cycle, the gripper jaws will have sized and tensioned the upper materials, as will presently appear. If the shaft 1180

should be returned to the position shown in FIG. 79 before the outside former has moved downwardly, a coil spring 1232, FIG. 70, will return the finger 1196 to the position shown and as determined by engagement of the member 1192 with an adjustable stop 1234.

The shaft 1180 is shifted to the right from the position shown in FIG. 79 in response to the depression of the treadle 222, FIG. 2, which, as already explained, sets the gripper jaws 300, 302 into operation for use in lasting along the sides of a shoe. Referring to FIG. 3, 34 and 70, there is secured to the end of the shaft 290 opposite to that to which the arm 288, FIG. 4, is secured, an arm 1240 which is provided with a slot 1242. Pivotally mounted on a screw stud 1244, carried by an angular support 1246 which is secured to the aforementioned block 1162, FIG. 71, is a bell-crank lever 1246. This lever has a horizontally extending arm 1248 to which there is secured a link 1250 carrying at its lower end a pin 1252 which projects through the slot 1242, FIG. 34. The other arm 1254 of this bell-crank lever is bifurcated and carries two pins 1256, 1256 which project through openings 1258, 1258 in the bushing 1168 and into the groove 1182 in the shaft 1180, FIG. 78. With this arrangement, when the treadle 222 is depressed, shaft 1180 will be shifted to the right from the position shown in FIG. 79, thereby connecting the arm 1200 to this shaft and hence to the operating finger 1196.

In addition to the welt guide 1106, the herein illustrated machine is provided with a welt gage 1260, FIGS. 34, 62, 64, 83, 86, 87 and 94. Referring to FIG. 62, there is secured to the post 818, by means of a screw 1262, a bracket 1264. The welt gage 1260, which has a shouldered portion 1266 for engaging the welt, is adjustably secured, by means of a screw 1268, to a rocker arm 1270, and this arm, in turn, is pivotally mounted on the lower end of a bracket 1264 by means of a pin 1272. A coil spring 1274, interposed between a portion of the rocker arm 1270 and the bracket 1264, tends to hold the rocker arm yieldingly in the position shown in FIG. 62 and as determined by the engagement of cooperating surfaces on the rocker arm and bracket. Thus the rocker arm and welt gage which is carried thereby may be swung in a clockwise direction about the pin 1272 against the resistance of the spring 1274, by the welt W, and yet its shouldered surface 1266 will constantly engage the edge of the welt to locate it relatively to the shoe, which, in turn, is located in a lateral direction by the anvil 812 received within the space beneath the insole rib R, see especially FIG. 94.

As the upper materials U are gripped, tensioned and drawn inwardly over the bottom of the shoe, successively, in different locations along a marginal edge of the bottom of the shoe, there will be a tendency, because of the fullness of the upper materials, for these materials to bulge outwardly and, unless this fullness is evenly distributed along the entire marginal edge of the shoe bottom, an unduly large bunch will develop as the lasting operation proceeds from the breast line to the tip line on one side of the shoe and from the tip line to the breast line on the opposite side of the shoe. In order to avoid this condition, the herein illustrated machine is provided with means for evenly distributing this fullness of the upper materials along the marginal edge of the shoe bottom as the lasting operation proceeds. This means comprises an upper deflecting finger 1280, FIGS. 34, 87, 94-101, which is pivotally mounted by means of a bolt 1282 on a supporting bracket 1284, secured to the lower end of the housing 824, see especially FIG. 87. A leaf spring 1286 holds the finger 1280 yieldingly in the position shown in FIG. 87 and as determined by the engagement of this finger with a stop pin 1288. Formed integrally with the finger is an upwardly projecting end portion 1290 which is in alignment with an abutment member

1292 mounted on the lower portion 864 of the lever 866 which, as has been explained above, is rocked in a counterclockwise direction, FIGS. 34 and 87, to project the auxiliary support 852 to its operative position. As will be quite apparent, each time the auxiliary support is thus projected to its operative position, the finger 1280 will be rocked in a clockwise direction from the position shown in FIGS. 34, 87, 94, 95, 100 and 101 to the position shown in FIGS. 96, 97, 98 and 99. This rocking movement occurs after the marginal portion of the upper materials U has been seized by the gripper jaws 300, 302, and therefore the finger 1280 will engage the marginal portion of the upper materials and draw them toward the gripper jaws as indicated by the arrow in FIG. 99. Thus, during each operation of the gripper jaws, a portion of the looseness of the upper materials is moved toward the gripper jaws and in this way the fullness is evenly distributed from point to point along the marginal portion of the shoe bottom as the lasting operation proceeds.

Referring especially to FIGS. 90 to 101, the operation of the machine, which perhaps should be generally understood from the preceding detailed description of its several operating elements and associated mechanisms, will now be outlined. As is explained in the patent to Pear soll et al., referred to above, the shoe to be lasted will, when presented to the machine of this invention, have been lasted at the heel end with tacks, in the usual manner, and at its toe end in a bed lasting machine with the lasting margin of the upper materials U secured to the flat rib R by means of a suitable adhesive, see FIGS. 90 to 93. The operator first presents the shoe to the machine, as shown in FIG. 94, with the anvil 812 inserted beneath the flat rib adjacent to the breast line on one side of the shoe and with the bottom of the insole held up against the anti-friction ball 814 in the shoe rest 810, FIG. 95. Upon depression of the treadle 222, the machine is set into operation with both the grippers and the staple forming and driving mechanism activated. Thus, the lasting margin of the upper material will be seized by the gripper jaws 300, 302 and tensioned heightwise of the last and then drawn inwardly over the bottom of the shoe, close to and parallel with the rib R, see FIGS. 97 to 100. During this tensioning operation, which occurs in an early part of the operating cycle, the shoe is supported against the pull of the gripper by the anvil 812 and the auxiliary support 852 which will have been projected to its operative position shown in FIGS. 96 to 100, and the lasting margin of the upper materials in a location ahead of the grippers, considered in the direction of feed, will be engaged by the upper deflecting member 1280, thus causing any excess looseness of the upper materials to be taken up by the action of the gripper jaws in tensioning the upper, as indicated in FIG. 99.

Shortly after the operating elements reach the positions in which they are shown in FIG. 100, and with the upper held under tension by the gripper jaws 300 and 302, the nozzle 418 descends to clamp the welt W and lasting margin of the upper materials indicated generally by the reference character U against the rib R and anvil 812, whereupon the staple driver 404 is operated to drive a staple "s" through the welt, upper materials and insole rib and to clench the staple against the anvil. Upon such operation of the staple driver, the auxiliary support 852 is retracted to its inoperative position, as shown in FIG. 95, and the upper deflector 1280 will be returned by its associated spring to its inoperative position. Next, the welt gripper jaws 1000 and 1004, which earlier in the operating cycle had been closed to grip the welt, are operated to feed the shoe, through the welt which is now secured thereto, and thus to present the shoe in position for the action of the grippers and staple forming and driving mechanism in the next successive location. During this feeding of the shoe by means of the welt gripper jaws, which action is, of course, facilitated by the pre-

vious retraction of the auxiliary supporting member 852, the shoe is guided and maintained in proper operating position with the angle of the rib held against the anvil 812 by the operator.

5 This opening cycle is repeated following each feeding of the shoe and so long as the operator keeps his foot on the treadle 222, until the lasting operation has proceeded to about the tip line on that side of the shoe, in which location the upper is already secured to the flat rib R by cement, as indicated above. Therefore, the operator now shifts his foot from the treadle 222 to the treadle 220, thus bringing the operation of the upper tensioning gripper to a stop while the operation of the staple forming and driving mechanism, as well as the shoe feeding mechanism, continues. As the shoe is thus fed along in predetermined increments, the staple forming and driving mechanism, now set to form and drive a long staple, is operated at each successive location to insert a long staple through the lasting margin, upper materials including a

10 box toe, the insole rib, and to clench this staple on the anvil as before. When the tip line on the opposite side of the shoe is reached, the operator returns his foot to the treadle 222, thus setting the gripper into operation again and causing the staple forming and driving mechanism to be set for driving a short staple as the lasting operation proceeds from this location up to the breast line on that side of the shoe and until terminated by the release

15 of the treadle 222.

It will be understood that immediately before the 20 gripper jaws 300, 302 are moved outwardly to seize the lasting margin of the upper materials, the welt guide 1106 will be rocked in a counterclockwise direction to the position shown in FIGS. 88, 99 and 101, thereby elevating the welt W out of the way of the gripper jaws. As the nozzle 418 subsequently descends to staple driving position, the 25 welt guide is rocked in the opposite direction to return the welt to a generally flattened position parallel to the bottom of the shoe, in which position it is held while the staple is being driven and also during the subsequent 30 operation of the welt gripper jaws 1000 and 1004 to feed the shoe.

Having thus described our invention, what we claim as new and desire to secure by Letters Patent of the United States is:

- 45 1. A machine for lasting shoes having a power operated gripper for tensioning the upper materials of a shoe over its last, successively, in different locations along the marginal edge of the shoe bottom, control means for selectively rendering said gripper operative or inoperative, mechanism for forming and inserting fastenings through the 50 lasting margin of the upper materials and an insole rib in each of said locations, means for varying the operation of said mechanism to provide long or short fastenings, and means including a foot treadle movable by the operator for simultaneously actuating said gripper control means and said fastening length varying means during the 55 operation of the machine.
2. A machine for lasting shoes having a power operated gripper for tensioning the upper materials of a shoe over 60 its last, successively, in different locations along the marginal edge of the shoe bottom, control means for selectively rendering said gripper operative or inoperative, mechanism for forming and inserting staples through the lasting margin of the upper materials and an insole rib in each of said locations, means for varying the operation of said mechanism to provide long or short staples, and means including a foot treadle for simultaneously actuating said gripper control means and said staple length varying means during the operation of the machine.
- 65 3. A machine for lasting shoes having a power operated gripper for tensioning the upper materials of a shoe over 65 its last, successively, in different locations along the marginal edge of the shoe bottom, control means for selectively rendering said gripper operative or inoperative, mechanism for forming and inserting fastenings through the 70 lasting margin of the upper materials and an insole rib in each of said locations, means for varying the operation of said mechanism to provide long or short staples, and means including a foot treadle for simultaneously actuating said gripper control means and said staple length varying means during the operation of the machine.
- 75

ing margin of the upper materials and an insole rib in each of said locations, means for varying the operation of said mechanism to provide long or short fastenings, and means including a foot treadle movable by the operator for simultaneously actuating said gripper control means and said fastening length varying means during the operation of the machine, said last-named means being arranged to cause the fastening forming and inserting mechanism to form and insert short fastenings when the gripper is rendered operative and to form and insert long fastenings when the gripper is rendered inoperative.

4. A machine for lasting shoes having a power operated gripper for tensioning the upper materials of a shoe over its last, successively, in different locations along the marginal edge of the shoe bottom, control means for selectively rendering said gripper operative or inoperative, mechanism for forming and inserting staples through the lasting margin of the upper materials and an insole rib in each of said locations, means for varying the operation of said mechanism to provide long or short staples, and means including a foot treadle for simultaneously actuating said gripper control means and said staple length varying means during the operation of the machine, said last-named means being arranged to cause the staple forming and inserting mechanism to form and insert short staples when the gripper is rendered operative and to form and insert long staples when the gripper is rendered inoperative.

5. A machine for lasting shoes having a power operated gripper for tensioning the upper materials of a shoe over its last, successively, in different locations along the marginal edge of the shoe bottom as the shoe is fed along relatively to said gripper, mechanism for forming and inserting fastenings through the lasting margin of the upper materials and the rib of an insole on the last in each of said locations, guide means adapted to engage said insole rib for positioning the shoe relatively to the fastening inserting means and for supporting the shoe laterally against the pull of the gripper, an auxiliary support movable from a retracted and inoperative position remote from the rib to an operative position to engage the rib during the operation of said gripper, and means operable in time relation to said gripper for so moving the auxiliary support.

6. A machine for lasting shoes having a power operated gripper for tensioning the upper materials of a shoe over its last, successively, in different locations along the marginal edge of the shoe bottom as the shoe is fed along relatively to said gripper, mechanism for forming and inserting fastenings through the lasting margin of the upper materials and the rib of an insole on the last in each of said locations, a fastening clinching anvil adapted to engage said insole rib in a location offset from the gripper for positioning the shoe relatively to the fastening inserting means and for supporting the shoe laterally against the pull of the gripper, an auxiliary support movable from a retracted and inoperative position remote from the rib to an operative position to engage the rib adjacent to said anvil and substantially in alinement with the direction of the pull applied to the upper materials by said gripper during the operation of said gripper, and means operable in time relation to said gripper for so moving the auxiliary support.

7. A machine for lasting shoes, having a power operated gripper for tensioning the upper materials of a shoe over its last, successively, in different locations along the marginal edge of the shoe bottom as the shoe is fed along relatively to said gripper, mechanism for forming and inserting staples through the lasting margin of the upper materials and the rib of an insole on the last in each of said locations, guide means adapted to engage said insole rib for positioning the shoe relatively to the staple inserting means and for supporting the shoe laterally against the pull of the gripper, an auxiliary support movable from a retracted inoperative position remote from the rib to an

operative position to engage the rib during the operation of said gripper, and means operable in time relation to said gripper for so moving the auxiliary support.

8. A machine for lasting shoes having a power operated gripper for tensioning the upper materials of a shoe over its last, successively, in different locations along the marginal edge of the shoe bottom as the shoe is fed along relatively to said gripper, mechanism for forming and inserting staples through the lasting margin of the upper materials and the rib of an insole on the last in each of said locations, a staple clinching anvil adapted to engage said insole rib in a location offset from the gripper for positioning the shoe relatively to the staple inserting mechanism and for supporting the shoe laterally against the pull of the gripper, an auxiliary support movable from a retracted and inoperative position remote from the rib to an operative position to engage the rib adjacent to said anvil and substantially in alinement with the direction of the pull applied to the upper materials by said gripper during the operation of said gripper, and means operable in time relation to said gripper for so moving the auxiliary support.

9. A machine for lasting shoes having a power operated gripper for tensioning the upper materials of a shoe over its last, successively, in different locations along the marginal edge of the shoe bottom as the shoe is fed along relatively to said gripper, control means for selectively rendering said gripper operative or inoperative, mechanism for forming and inserting fastenings through the lasting margin of the upper materials and the rib of an insole on the last in each of said locations, guide means adapted to engage said insole rib for positioning the shoe relatively to the fastening inserting means and for supporting the shoe laterally against the pull of the gripper, an auxiliary support movable from a retracted and inoperative position remote from the rib to an operative position to engage the rib during the operation of the gripper, and means for so moving the auxiliary support in time relation to said gripper when the gripper is rendered operative by said control means.

10. A machine for lasting shoes having a power operated gripper for tensioning the upper materials of a shoe over its last, successively, in different locations along the marginal edge of the shoe bottom as the shoe is fed along relatively to said gripper, control means for selectively rendering said gripper operative or inoperative, mechanism for forming and inserting fastenings through the lasting margin of the upper materials and the rib of an insole on the last in each of said locations, a fastening clinching anvil adapted to engage said insole rib in a location offset from the gripper for positioning the shoe relatively to the fastening inserting mechanism and for supporting the shoe laterally against the pull of the grippers, an auxiliary support movable from a retracted and inoperative position remote from the rib to an operative position to engage the rib adjacent to said anvil and substantially in alinement with the direction of the pull applied to the upper materials by said gripper during the operation of the gripper, and means for so moving the auxiliary support in time relation to said gripper when the gripper is rendered operative by said control means.

11. A machine for lasting shoes having a power operated gripper for tensioning the upper materials of a shoe over its last, successively, in different locations along the marginal edge of the shoe bottom as the shoe is fed along relatively to said gripper, control means for selectively rendering said gripper operative or inoperative, mechanism for forming and inserting staples through the lasting margin of the upper materials and the rib of an insole on the last in each of said locations, guide means adapted to engage said insole rib for positioning the shoe relatively to the staple inserting mechanism and for supporting the shoe laterally against the pull of the gripper, an auxiliary support movable from a retracted and inoperative position remote from the rib to an oper-

ative position to engage the rib during the operation of the gripper, and means for so moving the auxiliary support in time relation to said gripper when the gripper is rendered operative by said control means.

12. A machine for lasting shoes having a power operated gripper for tensioning the upper materials of a shoe over its last, successively, in different locations along the marginal edge of the shoe bottom as the shoe is fed along relatively to said gripper, control means for selectively rendering said gripper operative or inoperative, mechanism for forming and inserting staples through the lasting margin of the upper materials and the rib of an insole on the last in each of said locations, a staple clinching anvil adapted to engage said insole rib in a location offset from the gripper for positioning the shoe relatively to the staple inserting mechanism and for supporting the shoe laterally against the pull of the gripper, an auxiliary support movable from a retracted and inoperative position remote from the rib to an operative position to engage the rib adjacent to said anvil and substantially in alinement with the direction of the pull applied to the upper materials by said gripper during the operation of the gripper, and means for so moving the auxiliary support in time relation to said gripper when the gripper is rendered operative by said control means.

13. A machine for lasting shoes having a power operated gripper for tensioning the upper materials of a shoe over its last, successively, in different locations along the marginal edge of the shoe bottom as the shoe is fed along relatively to said gripper, control means for selectively rendering said gripper operative or inoperative, mechanism for forming and inserting fastenings through the lasting margin of the upper materials and the rib of an insole on the last in each of said locations, guide means adapted to engage said insole rib for positioning the shoe relatively to the fastening inserting means and for supporting the shoe laterally against the pull of the gripper, an auxiliary support movable from a retracted and inoperative position remote from the rib to an operative position to engage the rib during the operation of the gripper, means for so moving the auxiliary support in time relation to said gripper when the gripper is rendered operative by said control means, and a latch for holding the auxiliary support in operative position during the operation of the gripper.

14. A machine for lasting shoes having a power operated gripper for tensioning the upper materials of a shoe over its last, successively, in different locations along the marginal edge of the shoe bottom as the shoe is fed along relatively to said gripper, control means for selectively rendering said gripper operative or inoperative, mechanism for forming and inserting fastenings through the lasting margin of the upper materials and the rib of an insole on the last in each of said locations, a fastening clinching anvil adapted to engage said insole rib in a location offset from the gripper for positioning the shoe relatively to the fastening inserting mechanism and for supporting the shoe laterally against the pull of the grippers, an auxiliary support movable from a retracted and inoperative position remote from the rib to an operative position to engage the rib adjacent to said anvil and substantially in alinement with the direction of the pull applied to the upper materials by said gripper during the operation of the gripper, means for so moving the auxiliary support in time relation to said gripper when the gripper is rendered operative by said control means, and a latch for holding the auxiliary support in operative position during the operation of the gripper.

15. A machine for lasting shoes having a power operated gripper for tensioning the upper materials of a shoe over its last, successively, in different locations along the marginal edge of the shoe bottom as the shoe is fed along relatively to said gripper, control means for selectively rendering said gripper operative or inoperative, mechanism for forming and inserting staples through the lasting margin

gin of the upper materials and the rib of an insole on the last in each of said locations, guide means adapted to engage said insole rib for positioning the shoe relatively to the staple inserting mechanism and for supporting the shoe laterally against the pull of the gripper, an auxiliary support movable from a retracted and inoperative position remote from the rib to an operative position to engage the rib during the operation of the gripper, means for so moving the auxiliary support in time relation to said gripper when the gripper is rendered operative by said control means, and a latch for holding the auxiliary support in operative position during the operation of the gripper.

16. A machine for lasting shoes having a power operated gripper for tensioning the upper materials of a shoe over its last, successively, in different locations along the marginal edge of the shoe bottom as the shoe is fed along relatively to said gripper, control means for selectively rendering said gripper operative or inoperative, mechanism for forming and inserting staples through the lasting margin of the upper materials and the rib of an insole on the last in each of said locations, a staple clinching anvil adapted to engage said insole rib in a location offset from the gripper for positioning the shoe relatively to the staple inserting mechanism and for supporting the shoe laterally against the pull of the gripper, an auxiliary support movable from a retracted and inoperative position remote from the rib to an operative position to engage the rib adjacent to said anvil and substantially in alinement with the direction of the pull applied to the upper materials by said gripper during the operation of the gripper, means for so moving the auxiliary support in time relation to said gripper when the gripper is rendered operative by said control means, and a latch for holding the auxiliary support in operative position during the operation of the gripper.

17. A machine for lasting shoes having a power operated gripper for tensioning the upper materials of a shoe over its last, successively, in different locations along the marginal edge of the shoe bottom, means operating in time relation to the gripper for inserting a fastening through the lasting margin of the tensioned upper, a welt and a rib of an insole on the last in each of said locations to secure the tensioned upper in lasted position and to fasten the welt to the shoe, and means operating in time relation to said fastening inserting means for engaging the welt and then moving in a direction to feed the shoe relatively to said upper gripper and said fastening inserting means after the operation of the fastening inserting means.

18. A machine for lasting shoes having a power operated gripper for tensioning the upper materials of a shoe over its last, successively, in different locations along the marginal edge of the shoe bottom, means operating in time relation to the gripper for forming and inserting a staple through the lasting margin of the tensioned upper, a welt and a rib of an insole on the last in each of said locations, to secure the tensioned upper in lasted position and to fasten the welt to the shoe, and a gripper operating in time relation to the staple forming and inserting means for seizing the welt and then moving in a direction to feed the shoe relatively to said upper gripper and said staple forming and inserting means after the operation of the staple forming and inserting means.

19. A machine for lasting shoes having a power operated gripper for tensioning the upper materials of a shoe over its last, successively, in different locations along the marginal edge of the shoe bottom, means operating in time relation to the gripper for inserting a fastening through the lasting margin of the tensioned upper, a welt and a rib of an insole on the last in each of said locations to secure the tensioned upper in lasted position and to fasten the welt to the shoe, and a gripper having a jaw provided with a relatively smooth surface for engaging the grain side of the welt with a minimum of friction and

guide means to said first position prior to the operation of said staple forming and inserting means.

34. A machine for lasting shoes having a power operated gripper for tensioning the upper materials of a shoe over its last, successively, in different locations along the marginal edge of the shoe bottom, means for forming and inserting a staple through the lasting margin of the upper materials, a welt and the rib of an insole on the last in each of said locations to secure the tensioned upper in lasted position and to fasten the welt to the shoe, a staple clinching anvil for engaging the insole rib to position the shoe laterally with relation to the gripper and staple forming and inserting means, guide means comprising a member adapted to surround the welt in a location between the gripper and the staple forming and inserting means and pivotally mounted for movement into one position for holding the welt over the bottom of the shoe in generally parallel relation thereto and to another position for swinging the welt upwardly out of the way of the gripper, and means operated by a member associated with the staple forming and inserting means and in time relation to said gripper and said staple forming and inserting means for moving said guide means to said second position when the gripper is operated and for returning the guide means to said first position prior to the operation of said staple forming and inserting means.

35. A machine for lasting shoe having a power operated gripper for tensioning the upper materials of a shoe over its last, successively, in different locations along the marginal edge of the shoe bottom, means on one side of the gripper for inserting a fastening through the lasting margin of the upper materials and the rib of an insole on the last, to secure the tensioned upper to the rib in lasted position in each of said locations, and a member on the other side of the gripper for deflecting the lasting margin of the upper on that side of the gripper toward the bottom of the shoe during the operation of the gripper to tension the upper materials.

36. A machine for lasting shoes having a power operated gripper for tensioning the upper materials of a shoe over its last, successively, in different locations along the marginal edge of the shoe bottom, means for inserting a staple through the lasting margin of the upper materials and the rib of an insole on the last, to secure the tensioned upper to the rib in lasted position in each of said locations, a member on the other side of the gripper movable from an inoperative position to an operative position for deflecting the lasting margin of the upper on that side of the gripper toward the bottom of the shoe during the operation of the gripper to tension the upper materials, and means for moving said deflecting member to its operative position.

37. A machine for lasting shoes having a power operated gripper for tensioning the upper materials of a shoe over its last, successively, in different location along the marginal edge of the shoe bottom, means for inserting a fastening through the lasting margin of the upper materials and the rib of an insole on the last, to secure the tensioned upper to the rib in lasted position in each of said locations, guide means adapted to engage the insole rib for positioning the shoe relatively to the fastening inserting means and for supporting the shoe against the pull of the gripper, an auxiliary support movable from a retracted and inoperative position remote from the rib to an operative position to engage the rib, and a member on the other side of the gripper for deflecting the lasting margin of the upper on that side of the gripper toward the bottom of the shoe during the operation of the gripper to tension the upper materials.

38. A machine for lasting shoes having a power operated gripper for tensioning the upper materials of a shoe over its last, successively, in different locations along the marginal edge of the shoe bottom, means for inserting a staple through the lasting margin of the upper materials

and the rib of an insole on the last, to secure the tensioned upper to the rib in lasted position in each of said locations, guide means adapted to engage the insole rib for positioning the shoe relatively to the staple inserting means and for supporting the shoe against the pull of the gripper, an auxiliary support movable from a retracted and inoperative position remote from the rib to an operative position to engage the rib, a member on the other side of the gripper movable from an inoperative position to an operative position for deflecting the lasting margin of the upper on that side of the gripper toward the bottom of the shoe during the operation of the gripper to tension the upper materials, and means for moving said deflecting member and the auxiliary support to their operative positions.

39. A machine for lasting shoes having a power operated gripper for tensioning the upper materials of a shoe over its last, successively, in different locations along the marginal edge of the shoe bottom, control means for selectively rendering said gripper operative or inoperative, means for inserting a fastening through the lasting margin of the upper materials and the rib of an insole on the last to secure the tensioned upper to the rib in lasted position in each of said locations, guide means adapted to engage the insole rib for positioning the shoe relatively to the fastening inserting means and for supporting the shoe against the pull of the gripper, an auxiliary support movable from a retracted and inoperative position remote from the rib to an operative position to engage the rib, a member on the other side of the gripper movable from an inoperative position to an operative position for deflecting the lasting margin of the upper on that side of the gripper toward the bottom of the shoe during the operation of the gripper to tension the upper materials, and means operable by said control means for moving said deflecting member and the auxiliary support to their operative positions when said gripper is rendered operative.

40. A machine for lasting shoes having a power operated gripper for tensioning the upper materials of a shoe over its last, successively, in different locations along the marginal edge of the shoe bottom, control means for selectively rendering said gripper operative or inoperative, means for inserting a staple through the lasting margin of the upper materials and the rib of an insole on the last, to secure the tensioned upper to the rib in lasted position in each of said locations, guide means adapted to engage the insole rib for positioning the shoe relatively to the staple inserting means and for supporting the shoe against the pull of the gripper, an auxiliary support movable from a retracted and inoperative position remote from the rib to an operative position to engage the rib, a member on the other side of the gripper movable from an inoperative position to an operative position for deflecting the lasting margin of the upper on that side of the gripper toward the bottom of the shoe during the operation of the gripper to tension the upper materials, and means operable by said control means for moving said deflecting member and the auxiliary support to their operative positions when said gripper is rendered operative.

41. A machine for lasting shoes having a power operated gripper for tensioning the upper materials of a shoe over its last, successively, in different locations along the marginal edge of the shoe bottom, control means for selectively rendering said gripper operative or inoperative, means on one side of the gripper for inserting a fastening through the lasting margin of the upper material and the rib of an insole on the last to secure the tensioned upper to the rib in lasted position in each of said locations, a member on the other side of the gripper movable from an inoperative position to an operative position for deflecting the lasting margin of the upper on that side of the gripper toward the bottom of the shoe

shoe during the operation of the gripper to tension the upper materials, and means operable by said control means for moving said deflecting member to its operative position when said gripper is rendered operative.

42. A machine for lasting shoes having a power operated gripper for tensioning the upper materials of a shoe over its last, successively, in different locations along the marginal edge of the shoe bottom, control means for selectively rendering said gripper operative or inoperative, means on one side of the gripper for inserting a 10 staple through the lasting margin of the upper materials and the rib of an insole on the last, to secure the tensioned upper to the rib in lasted position in each of said locations, a member on the other side of the gripper movable from an inoperative position to an operative posi- 15

tion for deflecting the lasting margin of the upper toward the bottom of the shoe during the operation of the gripper to tension the upper materials, and means operable by said control means for moving said deflecting member to its operative position when said gripper is rendered operative.
